BLIND FASTENER FOR WALL AND CEILING
BOARDS

Frederick E. Starr, Belzoni, Miss.

Application September 12, 1936, Serial No. 100,529

6 Claims. (Cl. 20—4)

The invention relates to wall and ceiling fasteners and more especially to concealed or blind fasteners for wall and ceiling boards.

The primary object of the invention is the provision of a fastener of this character, wherein the same when applied to the studs or floor joists and have fastened thereby fiber boards or other coverings, of natural or artificial composition for walls and ceiling such fasteners will be concealed and the boards will be free for expansion and contraction resultant from climatic changes and particularly when heating an enclosure without liability of the boards becoming loose or accidentally detached.

Another object of the invention is the provision of a fastener of this character, wherein the necessity for the nailing of the wall and ceiling boards is entirely eliminated and such fasteners in association with the boards can be placed notwithstanding the fact that the studs may not be evenly separated from each other and the requirement for special tools for cutting the edges of the boards to assure proper fit will be avoided, there being no waste and a perfect finish can be had to the wall and ceiling on the laying thereof.

20 A further object of the invention is the provision of a fastener of this character, wherein the wall and ceiling boards will be prevented from curling at their ends and will be firmly and securely fastened in place with the fastener concealed from view.

25 A still further object of the invention is the provision of a fastener of this character, wherein the construction thereof is novel in form and is attached to the wall or ceiling board in a novel manner, the wall or ceiling boards being preferably of the fiber type and a smooth and uniform exposed surface is assured to the wall and ceiling.

30 A still further object of the invention is the provision of a fastener of this character, which is extremely simple in its construction, readily and easily applied and removed, thoroughly reliable and efficient in its operation, strong, durable, and inexpensive to manufacture.

35 With these and other objects in view, the invention consists in the features of construction, combination and arrangement of parts as will be hereinafter more fully described, illustrated in the accompanying drawing, which discloses the 40 preferred embodiment of the invention and pointed out in the claims hereunto appended.

In the accompanying drawing:

45 Figure 1 is a fragmentary elevation showing a wall built with the fasteners constructed in accordance with the invention.

Figure 2 is an enlarged sectional view on the line 2—2 of Figure 1.

Figure 3 is a sectional view on the line 3—3 of Figure 1.

Figure 4 is a perspective view of the fastener 5 per se.

Figure 5 is a perspective view of a modified form but used jointly with the preferred form.

Similar reference characters indicate corresponding parts throughout the several views in 10 the drawing.

Referring to the drawing in detail, A designates generally portions of studding of the framework of an enclosure and B boards of the fiber type adaptable for erection of walls or ceilings while C 15 designates generally a fastener constituting the present invention and hereinafter fully described.

The fastener D is in the form of a clip made from a single sheet metal blank which is split from opposite ends to provide an intermediate 20 solid portion 10 which is coextensive with the longitudinal extent of said blank. The splits from opposite edges allow for the reverse bending of such blank to provide inner and outer wings 11 and 12, respectively, these being reversely disposed to each other and at right angles to the intermediate portion 10 thus effecting between the wings seats 13 for accommodating therein edge tongues 14 and 15, respectively, which are cut into each board B at opposite edges thereof 25 and thus effecting an underlap tongue 14 and an overlap 17, respectively, thereto. Thus in the laying of the boards B edge to edge they will be disposed in overlapped relation to each other as is clearly shown in Figure 2 of the drawing.

30 The edge tongues 14 and 15 have bevels 18 so as to permit the easy seating of these tongues in the clip or fastener before described and facilitate expansion and contraction of the interfitted planking or boarding in the expansion groove 35 15'. Each clip is fastened by nails or other fasteners 19 to a stud A or a floor sill at the ceiling side thereof and such nails or fasteners 19 are passed through holes 20 in the wings 11 and 12 and driven into the studding or sill while the 40 tongues 14 and 15 are introduced into the seats 13 between the wings 11 and 12. Thus the clip having the wings 11 and 12 in opposite directions becomes the locking terminal between adjacent boards B and by the overlaps of these boards the 45 50 said clips are concealed from view, adequate room being had for expansion and contraction of the wall and ceiling covering in the expansion groove 15'.

In Figure 5 of the drawing there is shown a 55

modification of fastener which supplements the fastener hereinbefore described and comprises a substantially U-shaped clip 21 having the inner and outer wings 22 and 23, respectively, at right angles to an intermediate straight portion 24. This clip 21 is a terminal lock for each end of the board B and such clip is fastened similarly to the clip hereinbefore set forth. The end of the board seated in the clip 21 has the inset edge 10 tongue hereinbefore set forth.

In the setting or installation of a wall board, it is essential to start at any corner which is a left hand corner and at such point the clip 21 is fastened in place. The end of the plank 15 of the special construction as before mentioned is seated in such clip and the longitudinal edge portions of the plank are seated in the clips fastened to the studding A which latter clips are arranged horizontally on the respective studding 20 of the wall and thereafter successively additional planks are brought into place in the manner as shown in Figure 2 of the drawing.

What is claimed is:

1. The combination of planking, boarding or 25 other wall or ceiling covering having under and overlapped edge portions, edging tongues on said under and overlap portions, and fasteners having reversely extending wings and an intermediate straight portion providing seats between the 30 wings for accommodating the edge tongues of adjacent planks when disposed in underlap and overlap relation to each other.

2. The combination of planking, boarding or 35 other wall or ceiling covering having under and overlapped edge portions, edging tongues on said under and overlap portions, fasteners having reversely extending wings and an intermediate straight portion providing seats between the 40 wings for accommodating the edge tongues of adjacent planks when disposed in underlap and overlap relation to each other, and means passed only through the fasteners for securing the same to supports for said planks and having the means 45 and said fasteners concealed by the latter.

3. The combination of planking, boarding or 50 other wall or ceiling covering having under and overlapped edge portions, edging tongues on said under and overlap portions, fasteners having reversely extending wings and an intermediate

straight portion providing seats between the wings for accommodating the edge tongues of adjacent planks when disposed in underlap and overlap relation to each other, means passed only through the fasteners for securing the same to 5 supports for said planks and having the means and said fasteners concealed by the latter, and a supplemental U fastener engageable with an end of each plank and concealed by an overlap thereof.

4. The combination of a planking, boarding or other wall or ceiling covering having under and overlapped edge portions, edging tongues on said under and overlap portions and having fastening and expansion grooves, and fasteners having reversely extending wings and an intermediate straight portion providing seats between the wings for accommodating the edge tongues of adjacent planks when disposed in underlap and overlap relation to each other. 10

5. The combination of planking, boarding or other wall or ceiling covering having under and overlapped edge portions, edging tongues on said under and overlap portions and having fastening and expansion grooves, fasteners having reversely extending wings and an intermediate straight portion providing seats between the wings for accommodating the edge tongues of adjacent planks when disposed in underlap and overlap relation to each other, and means passed 15 only through the fasteners for securing the same to supports for said planks and having the means and said fasteners concealed by the latter. 20

6. The combination of planking, boarding or other wall or ceiling covering having under and overlapped edge portions, edging tongues on said under and overlap portions and having fastening and expansion grooves, fasteners having reversely extending wings and an intermediate straight portion providing seats between the 40 wings for accommodating the edge tongues of adjacent planks when disposed in underlap and overlap relation to each other, means passed only through the fasteners for securing the same to supports for said planks and having the means 45 and said fasteners concealed by the latter, and a supplemental U fastener engageable with an end of each plank and concealed by an overlap thereof. 30
